INVENTOR:

John S. Hall.
by Atty. A.B. Stoughton.

United States Patent Office.

JOHN S. HALL, OF PITTSBURG, PENNSYLVANIA.

Letters Patent No. 77,188, dated April 28, 1868.

IMPROVEMENT IN PLOUGHES.

The Schedule referred to in these Letters Patent and making part of the same.

TO ALL WHOM IT MAY CONCERN:

Be it known that I, JOHN S. HALL, of Pittsburgh, in the county of Allegheny, and State of Pennsylvania, have invented certain new and useful Improvements in Ploughs; and I do hereby declare the following to be a full, clear, and exact description of the same, reference being had to the accompanying drawings, making a part of this specification, in which—

Figure 1 represents a perspective view of the plough, taken from the land-side thereof.

Figure 2 represents in perspective the mould-board and land-side, and their attached parts, as detached and removed from the standard and its-attached parts.

Similar letters of reference, where they occur in the separate figures, denote like parts of the plough in both of the drawings.

My invention consists in making the mould-board and land-side of a plough in one piece, either cast together or united after casting them, and fastening the share to the mould-board, and the "renovator" to the land-side, so that, as these parts become worn out, they can be detached from the standard, and new ones applied to the same standard without reference to the beam or handles, as will be explained.

To enable others skilled in the art to make and use my invention, I will proceed to describe the same with reference to the drawings.

A represents the standard of the plough, to which the beam B is united in any of the usual well-known ways. The handle C is also united to the standard A, and the other handle, D, united to the one, C, by rings E in the common way. The lower end of the handle D is bolted to the mould-board F.

The mould-board F and the land-side G may be cast in one piece, or united into one piece after they are cast. The share and point H are made in a separate piece, and bolted to the mould-board, and the "renovator" I is made in a separate piece, and bolted to the land-side G; and when these parts are to be united to the standard, they are simply slipped up to the standard and bolted to it. When the mould-board and land-side become worn out, they can be detached from the standard and removed, and a new mould-board and land-side slipped on to the standard and bolted, and the plough be thus renewed without disturbing the beam, standard, and handle C.

What I claim as my invention, and desire to secure by Letters Patent, is—

A mould-board and land-side united in one piece, the former having the share and point attached to it, and the latter having the "renovator" or sole attached to it, and both united to a standard, A, so as to be readily removed when worn out, and replaced by another mould-board and land side, in the manner and for the purpose described.

JOHN S. HALL.
